UNITED STATES PATENT OFFICE.

HARRY L. BRIGHAM, OF BROCKTON, MASSACHUSETTS.

PNEUMATIC SHEET FEEDER.

Application filed February 16, 1920. Serial No. 359,029.

To all whom it may concern:

Be it known that I, HARRY L. BRIGHAM, a citizen of the United States, residing at Brockton, in the county of Plymouth and 5 State of Massachusetts, have invented new and useful Improvements in Pneumatic Sheet Feeders, of which the following is a specification.

This invention relates to apparatus for feeding paper sheets, and is particularly designed and adapted to feed separate sheets of paper to a printing press. Its main object, and the effect which it has accomplished, is to insure feeding of the sheets 10 separately, regardless of whether the paper handled is thin and flexible or is stiff and heavy. This is the object which all sheet feeding means have sought, but which none of the devices heretofore used has accomplished reliably. With all of the sheet-feeding mechanisms previously used, there is 15 liability of two sheets being picked up and fed to the press, wherefore it is necessary to have an attendant at hand constantly 20 watching the feeder to prevent this effect,— which is more likely to occur with thin sheets,—from happening.

The principle on which my feeder operates is the pneumatic principle, and it combines provisions for first attracting the sheet by pneumatic suction, and then lifting the sheet and feeder together, with provisions for applying the pneumatic suction upon the sheet progressively. Said progressive action consists in lifting and holding the forward edge of the sheet first, and then, as the sheet is carried toward the propelling rolls of the press, picking up the sheet at points progressively farther back 30 from the edge and releasing the parts first picked up. Finally the sheet is released altogether. Also there is preferably combined with the feeder having these principles, a blast pipe which directs a blast of air 35 against and under the advancing sheet, and delivers a film of air between that sheet and the next one beneath, whereby to diminish the friction between the sheet being fed and the underneath sheet, and avoid liability of the latter being dragged by the former to the propelling rolls of the press. Finally, an improved feature of the invention consists

in the construction of the feeder by which the edge of the sheet, when first pressed against it by air pressure, is somewhat bent 55 downward against the air blast at its forward edge, giving opportunity for the air blast to separate from it the next sheet below, making it impossible for such next sheet to be lifted by such interlocking of 60 fibres at the edges of sheets as sometimes occurs when a pile of sheets is cut or trimmed by a dull knife.

The exact nature of the invention and the principles embodied in it may be best understood by reference to the following description of a form of the invention which has been proved successful, and to the drawings furnished herewith, illustrating the same.

In the drawings:

Figure 1 is a sectional view of the main parts of the feeding device which forms my invention, in its association with the initial feed rolls of a printing press.

Figure 2 is a similar view, showing the 75 movable parts in a different position.

Figure 3 is an elevation of the feeder and the table carrying the paper sheets, as viewed from the rear, that is, from a position at the right of Figures 1 and 2.

Figure 4 is a sectional view on a larger scale of the feeder at the time of commencing the feeding stroke.

Figure 5 is a front elevation of the feeder, that is, an elevation as seen from the left of 85 Figure 4.

Like reference characters designate the same parts in all the figures, wherever they occur.

10 represents a table, on which sheets of 90 paper 11 to be printed are placed in a pile. 12 is a stationary front wall or abutment at the side of the table next to the printing press. For the purpose of this description, that side will be considered as the front. 95 13 and 14 are the initial propelling or feed rolls, by which the sheets are caught and propelled to the printing press. The rolls here shown are the common and well known type, and the press of which they are a part 100 is a standard commercial machine, wherefore it has been deemed unnecessary to illustrate said rolls more in detail or to show either their actuating means or the press

at all. It is sufficient to be understood that the lower roll 13 extends across the whole width of the press, and that the upper roll 14 is one of a pair or series of coaxial rolls, spaced apart, and each carried by an arm 15, which is secured to a rock shaft 16; means being provided to rock said rock shaft and so raise the rolls 14 (which may be called gripper rolls) when the sheet is advancing under the propulsion of the feeder, and to lower said gripper rolls upon the sheet when its advancing edge has been placed between the rolls; this motion also being timed with the movement of the press to deliver sheets correctly to the printing couple.

It is to be understood, also, that the table 10 is adjustable vertically in accordance with the number of sheets in the pile on it, and that it is automatically fed upward as the sheets are removed. The initial adjustment brings the top sheet of the pile at a given distance below the feeder, and thereafter the automatic feeding means maintains approximately the same distance of the successive top sheets below the feeder. The parts thus far described are known to all those acquainted with the printing art.

The new invention consists in the following-described parts, and in the combination thereof with the co-operating paper table and press feed rolls. A device 17, to which I may for the purpose of this description give the identifying name of feeder, is mounted in guides 18, 18, which permit it to travel back and forth in a path which runs toward the pick-up rolls 13 and 14. These guides are at the lower edges of two opposite walls of an enclosed chamber 19, which I may call for the purpose of this description a vacuum box. This vacuum box is supported by a beam 20, which extends across between the side frames 21. Enough looseness is provided between the feeder or feed plate and its guides to permit rise and descent of the feeder, and the walls of the vacuum box 19 are so disposed and limited that when the feeder is raised it substantially makes contact with the edges of the box and closes it. The feeder is made with a continuous upper surface, so shaped with reference to its path of movement that when thus raised it travels in contact with the edges of the open box. Preferably this surface is plane, but conceivably it may be either concave or convex; the guides and the immediately adjacent edges of the box being then appropriately formed to bring this surface into close enough proximity for the purpose.

Extending entirely through the feeder, from its top to its bottom surfaces, are passages 22, of which there is a sufficiently large number in a series extending generally from front to rear. Preferably I provide

65 two or more rows of such passages, but I may provide only one row or series. Likewise the feeder is longer than the front to rear width of the suction box, and its stroke is limited in such degree that at each arrest and reversal it wholly underlies the box, and continues to act as a closure for the open bottom thereof.

Various mechanisms may be provided for reciprocating the feeder in time with the movements of the press, and a suitable form of mechanism is shown in Figures 1, 2 and 3. A bell crank lever, having a long arm 23 and a short arm 24, is secured to a rock shaft 25, supported by brackets 26 and 27. The long arm 23 is connected by a link 28 with the forward end of the feeder, and the rock shaft 25 is oscillated by any suitable mechanism to move the feeder back and forth at the proper time.

A tube 29 rises from the suction box, and is connected with a pipe 30, which leads to the intake of a blower or vacuum pump or other suitable means for exhausting air. At its opposite ends the tube 29 is provided with valve seats 31 and 32, with which cooperate respectively valves 33 and 34 carried by a valve rod 35. A rocker 36, on a pivot 37, supported from the bracket 26, is engaged by a sliding connection with the bell crank lever arm 24, and has a forked end 38, which embraces the valve rod 35 and plays between adjustable abutments 39 and 40 on said rod. When the forked arm rises and strikes the abutment 39, it closes the valve 34 against seat 32; and when it descends, striking the stop 40, it opens valve 34 and closes valve 33 against seat 31. 41 and 42 represent guides for this rod, and 43 illustrates in a conventional way as a screw, threaded through the side of tube 29 and bearing on rod 35, an operative means for applying friction to hold the rod in either of its extreme positions, and particularly to prevent it from dropping by gravity from the raised position. Various other types of friction may be applied for this purpose, and other forms of lost motion may be provided between the valve and its actuating means for the same purpose that the lost motion connections just described are provided. This purpose is to shift the valve at or near the time of each reversal of the feeder, and to allow the valves to remain stationary in one position throughout the feeding stroke of the feeder and in the other position throughout the return stroke.

In the operative arrangement the feeder moves back and forth at a sufficient distance above the topmost sheet of paper so as not to touch the paper on its return stroke. Then the looseness provided in its guideways enables it to rise a considerable distance at the commencement of its feeding stroke. This distance may be one-eighth of an inch, more or less; and the distance be-

tween the feeder when making its return stroke and the top of the pile may be as much as one-quarter of an inch, or as little as will suffice to avoid contact.

- 5 The feeder may be made of wood or of metal, provided that in specific gravity or construction it is light enough to enable it to be lifted by air pressure or impact. Various modes of construction may be practiced 10 to get these results. The passages previously mentioned are spaced closely enough to bring at least one of them, and preferably two, in each row in communication with the vacuum box at the same time, whatever 15 may be the position of the feeder.

An important feature of the feeder is that its under side on the forward end is inclined upwardly, preferably on a curve, as shown at 44 in Figure 4. The foremost 20 passage or hole 22 preferably opens through a part of this inclined surface; and where there are two or more series of holes I prefer that the foremost holes of both series should open through the inclined surface, 25 and should be in a line approximately parallel with the edge of the sheet and somewhat back from the edge when the feeding stroke begins. The purpose and result of 30 the construction just described is to cause the advancing or forward edge of the sheet of paper when picked up by the feeder to project forward under the inclined part of the feeder, as well as to cause this edge, in the case of a thin and flexible sheet, to be 35 puckered and so bent away from the adjacent inclined surface. A part of the air blast delivered from the blast pipe is thus deflected by the feeder downward upon the upper side of the sheet at and near its edge, 40 and causes this edge to be bent down, with the effect of certainly separating the topmost sheet from the second sheet in case two sheets should have been picked up at once.

The blast pipe above mentioned is mounted 45 immediately in front of the abutment wall 12, in position to direct the blast of air issuing from it partly against the under side of the feeder, and also partly against the edges of the uppermost sheets in the 50 pile. The abutment wall 12 is cut away at 45° adjacent to the orifice of the pipe. Air under sufficient pressure is supplied by any suitable means to the blast pipe, and among the means suitable for the purpose are included 55 air compressors, pumps, and rotary blowers of various sorts. I may, indeed, exhaust air from the suction box and deliver it to the blast pipe by the same blower or pump, connecting the exhaust pipe 30 to 60 the intake of the blower or pump, and connecting the blast pipe with its outlet.

Now, in explaining the mode of operation of the feeder, let it be assumed that the feeder has just completed its return stroke. 65 It is then in the position shown in Figure

1, where it is fully retracted and has dropped a short distance from the bottom of the suction box. At this time the rocker 36, reaching the end of its movement, lowers the valve rod and so simultaneously opens 70 valve 34 and closes valve 33. Then the suction of the air pump exhausts air from the box 19, whereupon the outer air rushes through the passages 22. Some air, of course, passes between the feeder and the 75 adjacent edges of the box, but not enough to defeat the operation of the feeder because a sufficient amount flows through the holes 22 to lift the topmost sheet and hold it against the under side of the feeder. 80 When this has occurred, the holes 22 are stopped, and then the unbalanced pressure of air on the under side of the feeder raises it against the walls of the box, and at the same time still further raises the sheet. I 85 have found that the lifting force thus applied by the flow and unbalanced pressure of air induced by a rotary blower of approximately six inches in diameter is sufficient to pick up sheets of heavy cardboard, 90 and that it is likewise effective to lift and feed the thinnest and flimsiest paper made. I am able to regulate the amount of the unbalanced air pressure thus acting by providing in some part of the piping leading 95 from the vacuum box to the air pump a branch opening, controlled by a valve or damper, as indicated at 48 in Figure 3.

Sticking together of sheets frequently occurs in the case of thin paper, and has been 100 a fruitful cause of trouble and annoyance in the past. This may be due to various causes, including the bending over of sheets at the edges when cut by a dull knife, or the fraying out of fibres at the cut edges and the 105 interlocking of such fibres of adjacent sheets. Even if the sheets acted upon by my feeder should be fastened together in such a way, they are disassociated by the combined action of the suction and the air blast 110 from the pipe 45, assisted by the shape of the forward end of the feeder. This thin paper is somewhat drawn into the holes in the feeder, as shown in Figure 4, and the effect of thus drawing it in at the forward 115 holes is to bend the edge portion of the sheet between the holes away from the adjacent surface in a pucker or bow-shaped bend, as indicated in Figure 5. Due to this bending of the edge, the air current issuing 120 from the blast pipe strikes against the upper side of the sheet at this point and is thereby deflected so that it blows downwardly on the edge of the sheet, and bends down or causes fluttering of the part of the 125 sheet on which it blows. At each side of the feeder, however, the forward edge of the sheet is raised. The mechanical action of the bend likewise tends to open a space between the top sheet and the next sheet, and 130

if two sheets should be locked or adhered together, the bending down and fluttering of the front edges break apart the bond between them and air directed as above stated 5 enters and blows the sheets apart beyond any possibility of the next sheet being carried forward with the top sheet. Then the blast of air, spreading out, lifts the top sheet where it extends behind and on both sides 10 of the feeder and makes a film of air on which the sheet floats with little or no drag upon the next sheet.

All this occurs instantaneously, and at the same time the feeder commences its forward 15 travel. As it progresses, one hole after another at the rear of the box comes into the vacuum space, and at the same time the holes previously in that space pass out of it progressively. Thereby the feeder lifts the 20 sheet with a progressive action, always holding that part which is directly under the vacuum box, but releasing the forward edge during its advance. This travel is carried on until the forward edge of the sheet has been 25 brought to the point where it will be nipped by the propelling roller, and the progressive release of the forward part of the sheet allows its edge to sag until it rests on the roll 13 and is gripped. When the sheet has been 30 advanced thus far, the feeder ends its forward stroke, and at that time the rocker fork 38 strikes the abutment 39 and raises the valves, closing valve 34 and opening valve 33, whereupon the exhaustion of air 35 from the vacuum box ceases and the sheet is released. There is not such a tight fit between the edges of the vacuum box and the feeder as to prevent air from leaking into the box wherefore the pressure within the box 40 becomes equalized with the external air pressure as soon as the exhaust action ceases, and the feeder is able to drop by its own weight instantly, and the sheet is left free to be carried away by the propelling rolls.

45 It will be evident from the foregoing description that in this specification the term "forward," "front" and terms of like import, when used with respect to direction, signify the direction in which the feeder 50 moves when transferring a sheet from the pile to the press feed rolls; and when used with respect to position or location have a corresponding significance. The claims are to be construed in accordance with this definition.

What I claim and desire to secure by Letters Patent is:

1. A pneumatic sheet feeding means, comprising a feed member mounted to be movable back and forth in the feeding path over the sheets to be fed and having air passages, a vacuum chamber beneath which said feed member is arranged, with respect to which said member has a limited up and down 60 movement, and with which certain of the air 65

passages in said member communicate in each position of the feed member, means for withdrawing air from said vacuum chamber, and valve means constructed and arranged to control the outflow of air to said withdrawing means. 70

2. A sheet feeding apparatus, comprising the combination with a support adapted to hold a pile of separate sheets and propelling means for carrying said sheets away, of a 75 feeder movable back and forth over said support toward and away from said propelling means and having also a limited up and down movement, said feeder having a suction passage, and means for inducing flow 80 of air to said passage from beneath the feeder and for causing cessation of such flow alternately in proper time with the back and forth movements of the feeder for the purpose of lifting sheets from the support and 85 releasing them in proximity to the propelling means.

3. A sheet feeding apparatus, comprising in combination a support adapted to hold a pile of paper sheets, propelling means for 90 carrying away the sheets, a feeder movable over said support toward and away from said propelling means, and suction means for inducing flow of air through said feeder from beneath it while the feeder moves 95 toward the propelling means, whereby it is caused to lift the topmost sheet on the support and carry the same toward the propelling means, a guideway for said feeder arranged in a generally horizontal direction, 100 and with respect to which the feeder is adapted for a limited upward movement by the air pressure acting as a result of such suction against the lifted sheet.

4. A sheet feeding apparatus, comprising 105 a feeder mounted to travel in a given path and having a series of air passages opening in its under side and extending in the general direction of its feeding travel, means for moving said feeder back and forth in such 110 path, a support adapted to hold a stack of paper sheets under said feeder, a suction chamber arranged over the feeder in position to induce flow of air through said passages successively in the course of the feeding 115 movement of the feeder and means for alternately causing an intermitting outflow of air from said chamber in time with the feeding and return movement of the feeder, respectively. 120

5. A feeding means for paper sheets, embodying a vacuum chamber, a feeder arranged to form a closure for the under side of said vacuum chamber and mounted to move back and forth beneath the same, having a length as great as its said movement plus the dimension of the vacuum chamber in the direction of said movement, and having a series of passages arranged to pass progressively into and out of communication 125 130

with the interior of said chamber, means for exhausting air from the chamber, and means for so moving the feeder.

6. A feeding means for paper sheets, embodying a vacuum chamber, a feeder arranged to form a closure for the under side of said vacuum chamber and mounted to move back and forth beneath the same, having a length as great as its said movement 10 plus the dimension of the vacuum chamber in the direction of said movement, and having a series of passages arranged to pass progressively into and out of communication with the interior of said chamber, means for exhausting air from the chamber, and means 15 for so moving the feeder, the feeder having also provision for up and down movement and being light enough in weight to cause it to be raised by the air pressure from beneath when those passages in communication 20 with the vacuum chamber are covered by a paper sheet.

7. A pneumatic paper sheet feeding apparatus, comprising a back and forth moving feeder having a substantially plane under surface which is upwardly inclined at its forward end, and having also a series of through passages adapted to permit flow of air, the foremost passages being substantially side by side and opening in the said inclined part of the under surface, a support for a pile of paper sheets underneath said feeder, means for inducing draft of air through said forward passages when the 30 feeder is in position to bring such passages over said support somewhat back from the forward edge of a sheet supported thereon, whereby the sheet is applied by air pressure against the feeder and its forward edge,— 35 40 45

40 in the case of a sufficiently flexible sheet,—is puckered between the parts which underlie said forward passages, and means for directing a blast of air along the under surface of the feeder oppositely to its direction of feeding travel.

8. The combination with a back and forth moving feeder having a flat under surface upwardly inclined at its forward end, of means for reciprocating said feeder forward 50 and back, a blast nozzle arranged to deliver a blast of air along the under side of said feeder from the front toward the rear thereof, the feeder having passages through it including two passages abreast opening in 55 said inclined surface, and means for inducing flow of air through said passages from beneath the feeder whereby to cause the topmost sheet from a pile of sheets supported beneath and near the feeder to be applied 60 against the feeder, the arrangement of the forward passages causing a thin paper sheet when so pressed against the feeder with its forward edge beneath said inclined surface to be puckered as to said forward edge, 65 whereby the air blast is enabled to strike

against and above such edge and prevent the feeding of more than one sheet at one time.

9. A sheet feeding apparatus, comprising, in combination with a support adapted to hold a pile of separate sheets, a vacuum chamber above the sheets on said support and having an opening in its bottom, a feeder supported to travel back and forth beneath said opening and above the pile of sheets and having a length greater than that of the opening in the direction of such movements, whereby either end of the feeder is adapted to project beyond the opening, said feeder being arranged with provision for limited up and down movement and having a series of passages distributed throughout its length arranged to come into communication with the opening successively and to pass out of such communication successively in the course of the feeding travel of the feeder, means for exhausting air from the vacuum chamber, means for directing a blast of air under the feeder and against the front edge of the sheets so supported, and mechanism for moving the feeder back and forth.

10. In a pneumatic sheet feeding means, a reciprocating feeder having suction passages, means for supporting a pile of sheets beneath said feeder, the feeder being arranged to cause its forward end to pass beyond the edge of such pile in the feeding direction, and having its bottom surface adjacent to said forward edge inclined upwardly and forwardly from a point back of the forward edge of the sheets when the feeder is in position to commence its feeding travel, means for drawing air through said suction passages whereby to cause the uppermost sheet on the pile to be carried against the feeder, and a blast nozzle arranged to direct a current of air against said inclined surface and toward the pile of sheets.

11. In a pneumatic sheet feeding means, a reciprocating feeder having suction passages, means for supporting a pile of sheets beneath said feeder arranged to maintain the topmost sheet of the pile approximately at the same distance below the feeder at all times, the feeder being arranged to cause its forward end to pass beyond the edge of such pile in the feeding direction, means for drawing air through said suction passages whereby to cause the uppermost sheet on the pile to be carried against the feeder, and a blast nozzle arranged to direct a current of air between the sheet so lifted and the next sheet on the pile, being arranged to be lifted by suction when the sheet has been so applied against it.

12. In a pneumatic sheet feeding apparatus, a reciprocatably mounted feeder, mechanism for moving said feeder back and forth, a vacuum chamber over said feeder

having an open bottom for which the feeder forms a closure, the feeder being arranged with provision for limited up and down movement, inlet and outlet valves arranged respectively to control inflow of air to said chamber and outflow therefrom, means for exhausting air from the chamber, and mechanism timed with the movement of said

feeder for operating said valves to permit outflow of air from the chamber during the ¹⁰ feeding stroke of the feeder and inflow of air to the chamber at the end of said feeding stroke.

In testimony whereof I have affixed my signature.

HARRY L. BRIGHAM.
